UNITED STATES PATENT OFFICE.

WILLIAM S. ELLIOTT, OF PITTSBURGH, PENNSYLVANIA.

APPARATUS FOR TREATMENT OF LIQUIDS.

Application filed January 14, 1921. Serial No. 437,240.

To all whom it may concern:

Be it known that I, WILLIAM S. ELLIOTT, a citizen of the United States, residing at Pittsburgh, in the county of Allegheny and 5 State of Pennsylvania, have invented a new and useful Improvement in Apparatus for Treatment of Liquids, of which the following is a full, clear, and exact description, reference being had to the accompanying 10 drawings, forming part of this specification, in which:—

Figure 1 is a front elevation of one form of apparatus embodying my invention;

Figure 2 is a vertical section on the line 15 II—II of Figure 1; and

Figure 3 is a top plan view of the apparatus.

My invention has relation to apparatus for the separation of air and other dissolved 20 gases from water and other liquid; and more particularly to apparatus for use in carrying out the method of changing the phase of a sufficient percentage of the water to effect the removal therefrom of substantially all 25 of the air.

In the practice of said method a large amount of carbonates are released in the separator which causes an accumulation of scale and mud therein which it is necessary 30 to remove at frequent intervals. The heating of the water in the heater likewise produces more or less precipitation which necessitates frequent cleaning. Repairs to either the heater or the separator are sometimes required. An important feature of 35 the method is that it should be as continuous in its operation as is possible.

The object of the present invention is to provide apparatus of this character in which 40 the separating operations may be carried on continuously without interruption; and to this end the invention consists in providing apparatus having a plurality of chambers, some of which may be used either as heating 45 chambers or as separating chambers; together with the necessary connections to enable this to be done and also means whereby any one of the chambers may be isolated without affecting the operations in the 50 remaining chambers.

The nature of my invention will be best understood by reference to the accompanying drawings in which I have shown a preferred embodiment thereof, and which 55 will now be described, it being premised however that the apparatus is susceptible

of many different embodiments within the spirit and scope of the broader claims.

In these drawings the numeral 2 designates a vertical cylindrical casing, which 60 may be formed in superimposed sections and in which is divided interiorly into the three compartments, A, B and C by suitable partitions or separating walls 2^a and 2^b. 3 designates a steam supply connection having 65 two branches 3^a and 3^b which communicate respectively with the compartments A and B, each of these branches having a separate control valve 4 and 4^a.

5 designates a supply line for the liquid to 70 be treated, this also having the two branches 5^a and 5^b, each branch having therein a control valve 6 or 7, the valve 6 being controlled by a float 8 in the compartment A, and the valve 7 being controlled by a float 9 75 in the compartment B. Each of the branches 5^a and 5^b may also be provided with a manually operated gate valve 10^a. The valves 6 and 7 are controlled by the floats 8 and 9 to maintain a constant water 80 level in the respective compartments when in use. 11 designates a condenser having an exhaust connection at 12 with the compartment B, and another connection at 13 with the compartment C, each of these connections having an independent control valve 85 14 and 15, respectively. 16 designates an ejector for exhausting the non-condensable gases from the condenser and for assisting in maintaining a partial vacuum in 90 the chamber or chambers to which the condenser is connected.

17 designates a pipe having one branch 18 which communicates with the lower portion of the chamber A; a second branch 19 95 which communicates with the upper portion of the chamber B and a third branch 20 which communicates with the upper portion of the chamber C. Each of these three branches is provided with a manually actuated shut-off valve 21, 22 and 23, respectively. The branch 19 is also provided with a control valve 24 which is actuated by a float 25 in the chamber B. The branch 20 also has a control valve 26 actuated by a float 100 27 in the chamber C. The branch 19, enters a distributor 28 in the upper portion of the chamber B, this distributor acting to distribute the liquid over the corrugated pans 29 or other suitable distributing devices. 110 In like manner the branch 20 of the pipe 17 enters a similar distributor 30 in the upper

portion of the chamber C, this distributor distributing the liquid to the pans or other distributing devices 31 in said chamber C.

32 designates a pipe which has one branch 5 33 communicating with the lower portion of the chamber B; a second branch 34 communicating with the distributor 30 in the chamber C; and the third branch 35 communicating with the lower portion of the 10 chamber C. These three branches have respectively, the manually actuated control valves 36, 37 and 38. The branch 34 also has a control valve 39 which is actuated by a float 40 in the chamber C.

15 The arrangement of the chambers and their valve connections is such that the chamber A may be used as the heating chamber and either chamber B or C as a separating chamber; or the chamber B may be 20 used as the heater and the chamber C as the separator. In all cases the third chamber may be completely isolated so that it may be cleaned or repaired without interfering with the operations in the other two 25 chambers.

Taking first the condition in which the chamber A is employed as a heater and the chamber B as a separator, and the chamber C isolated or out of service: In this case the 30 valve 4 will be open and the valve 4^a closed; valve 36 is open and valve 38 closed; valves 23 and 37 are closed; valves 21 and 22 are open; valve 14 is open and valve 15 is closed; valves 6 and 10 are open and valves 7 and 10^a are closed.

With the valves in these positions steam and water will be delivered to the chamber A and heated water will be delivered to the chamber B. The water flowing over the 40 distributing device at the upper portion of the chamber A drops to the water level of the separator and the heated water is drawn out through the branch 18 of the pipe 17 and is delivered through the branch 19 into the distributor 28. The temperature of the 45 water in the heater A is preferably maintained at about 22° in excess of the temperature in the chamber B, by supplying a sufficient amount of heat for that purpose. The 50 temperature in the chamber B is maintained by the action of the condenser 11, through which a sufficient quantity of cooling water is supplied to maintain a definitely lower temperature in chamber B than the temperature 55 of the water in chamber A immediately before it enters the distributor 28. This difference in temperatures and pressures produces a change of phase of a sufficient percentage of the liquid as it enters the chamber B, to drive off or release the air and gas contained therein. The vapors released by this change in phase are then condensed in the condenser and the air and other non-condensable gases are drawn off through the condenser 16. For economical

operation the water which is supplied to the heater should be first used as the cooling water for the condenser to enable it thereby to absorb and return to the heater substantially all the heat energy which is dissipated by the maintenance of the vacuum in the separator.

When it is desired to isolate the chamber B, and to use the chamber A as the heater and the chamber C as the separator, the 70 steam connections to the chamber A are the same. As in the condition first described, the inlet water connections will be the same, but the valves 35, 22 and 37 will be closed and the valves 38 and 23 will be open. With this arrangement the water will leave the heater A through the branch 18 as before, but will pass down into the distributor 30 of the chamber C through the branch connection 20 and will be distributed over the 80 base 31. The valve 14 will be closed and the valve 15 open so that the chamber C will be connected directly with the condenser while a communication between the condenser and the chamber B is cut off. In this 85 case the treated liquid is taken off through the branch 35 of the pipe 32, instead of through the branch 33 of said pipe, as in the first described condition. In the third case in which the chamber A is isolated and the chamber B is used as the heater, and chamber C as the separator, the valve 4 will be closed, valve 4^a will be open, valves 6 and 10 will be closed and valves 7 and 10^a open; valves 22, 23 and 36^a in pipe 32 will be 90 closed, while valves 36, 37 and 38 will be open. Steam will now enter the chamber B and the liquid to be treated will also enter said chamber and after being heated will pass out through the branch 33 into the distributor 30 through the branch 34.

The advantages of my invention will be apparent since it provides apparatus of the character described in which the separation of air and other dissolved gases from liquids can be carried on continuously notwithstanding the necessity for cleaning and repairs. It will be obvious that the number and arrangements of the chambers can be widely varied as may also be the arrangement of the connections to and between the several chambers and of the controlling valves for such connections.

I claim:

1. Apparatus for separating gases from liquids, comprising a plurality of chambers, and connections whereby at least one of said chambers may be isolated from the others at will and at least one of said chambers may be used either as a liquid heating chamber or a chamber receiving heated liquid and separating gases therefrom, substantially as described.

2. Apparatus for separating gases from liquids, comprising a plurality of chambers,

- means for heating separately certain of said chambers, means for connecting said chambers in series, said last named means permitting any one of said chambers to be isolated while the remaining chambers are in operation, and means for separately withdrawing liquid from certain of said chambers, substantially as described. 5
3. Apparatus for separating gases from liquids, comprising at least three chambers, and connections whereby at least one of said chambers can be used interchangeably either as a heater with one of said chambers or as a separator with another of said chambers, substantially as described. 10
4. Apparatus for separating gases from liquids, comprising a plurality of chambers, connections therefor, and valves in said connections, whereby at least one of the chambers can be used interchangeably either as a heater with one of said chambers or as a separator with another of said chambers, substantially as described. 15
5. Apparatus for separating gases from liquids, comprising a plurality of chambers any two of which are adapted to be directly connected, at least two of said chambers having means whereby either a heated liquid or a heating medium may be supplied thereto, and a condenser independently connected to at least two of the chambers, substantially as described. 20
6. Apparatus for separating gases from liquids, comprising a plurality of chambers, at least two of said chambers having means whereby either a heating medium or a liquid heated by said medium may be supplied thereto, a condenser connected to at least two of the chambers, together with means for isolating any one of said chambers from the others, and also for isolating either of the chambers to which the condenser is connected from the condenser, substantially as described. 25
- 45 7. Apparatus for separating gases from liquids, comprising a plurality of chambers any two of which are adapted to be directly connected, and means whereby some of said chambers may be used interchangeably either as heating or as separating chambers, and also whereby any one of said chambers may be isolated, substantially as described. 30
8. Apparatus for separating gases from liquids, comprising a plurality of chambers any two of which may be directly connected independently of the others, means whereby a heating medium may be supplied at will to one of two connected chambers irrespective of which two are connected, and a vacuum condensing means adapted to be connected at will to the other of two connected chambers independently of the others, substantially as described. 35
9. Apparatus for separating air from gases, comprising a plurality of chambers
- any two of which may be directly connected independently of the others, means whereby a heating medium may be supplied at will to one of two connected chambers irrespective of which two are connected, and a condenser 70 adapted to be connected at will to the other of two connected chambers independently of the others, substantially as described.
10. Apparatus for separating gases from liquids, comprising at least three chambers, connections between said chambers whereby any two of said chambers may be directly connected, a condenser connected to at least two of the chambers, means for introducing a heating medium to at least two of said chambers, means for supplying a liquid to be treated to at least two of the chambers, and means in said connections for isolating any one of the chambers while the other chambers remain in operation, substantially 80 as described. 75
11. Apparatus for separating gases from liquids, comprising three chambers, a supply connection for the liquid to be treated leading to at least two of said chambers, supply connections for a heating medium also connected to each of the said two chambers, a connection for supplying the liquid heated in either of the said two chambers to the third chamber, and a similar connection between the second and third of said chambers, together with valves for controlling said connections, substantially as described. 90
12. Apparatus for separating gases from liquids, comprising three chambers, a supply connection for the liquid to be treated leading to at least two of said chambers, supply connections for a heating medium also connected to each of the said two chambers, a connection for supplying the liquid heated in either of the said two chambers to the third chamber, and a similar connection between the second and third of said chambers, each of said chambers having liquid distributing means therein, substantially 95 as described. 100
13. Apparatus for separating gases from liquids, comprising three chambers, a supply connection for the liquid to be treated leading to at least two of said chambers, supply connections for a heating medium also connected to each of the said two chambers, a connection for supplying the liquid heated in either of the said two chambers to the third chamber, and a similar connection between the second and third of said chambers, together with means for maintaining a substantially constant liquid level in each of said chambers, substantially as described. 110 115
14. Apparatus for separating gas from liquids, comprising three chambers any two of which may be directly connected to operate together, and means for maintaining a definite difference in pressure and tem- 120 125 130

perature conditions between either the first and second, the first and third, or the second and third of said chambers when operating together, substantially as described.

5 15. Apparatus for separating gases from liquids, comprising three chambers, means for supplying liquid to be heated to either one of two of said chambers, means for supplying a heating medium to either one of 10 said two chambers, a condenser connected with one of said two chambers and also to the third chamber, a liquid supply connection from the first of said two chambers to each of the other chambers and a liquid supply 15 connection from the second of said two chambers to the third chamber, substantially as described.

16. Apparatus for separating gases from liquids, comprising three chambers, means 20 for supplying liquid to be heated to either one of two of said chambers, means for supplying a heating medium to either one of said two chambers, a condenser connected with one of said two chambers and also to 25 the third chamber, a liquid connection from the first of said two chambers to each of the other chambers and a liquid supply connection from the second of said two chambers to the third chamber, together with 30 valves in said connections whereby any one of the three chambers may be isolated from

the others and from the condenser, substantially as described.

17. Apparatus for separating gases from liquids, comprising three chambers, means 35 for supplying liquid to be heated to either one of two of said chambers, means for supplying a heating medium to either one of said two chambers, a condenser connected with one of said two chambers and also to 40 the third chamber, a liquid supply connection from the first of said two chambers to each of the other chambers and a liquid supply connection from the second of said two chambers to the third chamber, together with means for removing the treated liquid 45 from either the second of the said two chambers or from the third chamber, substantially as described.

18. Apparatus for separating gases from 50 liquids, comprising at least three chambers arranged in axial alinement, means for separately supplying heat at will to at least either of two of said chambers, a condenser adapted to be separately connected at will 55 to at least either of two of said chambers, and flow connections between said chambers, substantially as described.

In testimony whereof I have hereunto set my hand.

WILLIAM S. ELLIOTT.
